EMIL BESSERT, OF FRONDENBERG-ON-THE-RUHR, GERMANY.

VALVE.

1,044,124.

Specification of Letters Patent.

Patented Nov. 12, 1912.

Application filed December 12, 1911. Serial No. 665,227.

To all whom it may concern:

Be it known that I, EMIL BESSERT, a citizen of the German Empire, and residing at Frondenberg-on-the-Ruhr, Germany, have 5 invented certain new and useful Improvements in Valves, of which the following is a specification.

My invention relates to valves, and a primary object is to provide an improved closure device for gases or liquids which possesses not only the good properties of stop-cocks but also those of valves.

When my device is open, it comprises between its branch pipes a smooth connecting 15 channel or duct, as in stopcocks, while when it is closed, its ports are closed by firmly pressed valve disks or the like, as in valves.

My improved device also has the good property of stopcocks in that, when changing 20 from fully closed to fully open, only a quarter turn is necessary, while, on the other hand, the bad properties of stopcocks, *e. g.*, burning fast, are entirely avoided.

My improved device is therefore particularly suitable as a blow-off valve for steam 25 boilers, because in such valves rapid opening, tight closure and a smooth passage obviating stoppage by small pieces of boiler scale are specially desirable features.

My improved closure device or valve comprises a box, provided with branch pipes, and containing a revoluble pipe adapted to be placed so that it establishes a smooth connection between two branches. When this 35 pipe is moved two valve bodies are simultaneously moved so that in their closed position they close the mouths of the branches, while in their open position in which the pipe forms the connecting channel, they are 40 drawn back from the branches.

The accompanying drawing shows by way of example a closure device in which two 45 balls are used as valve bodies, each of which can rotate freely in a holder pivoted on the revoluble pipe, so that when the pipe is rotated the balls can enter into the mouths of the branches or are moved away by it.

In said drawing:—Figure 1 is a vertical 50 sectional elevation, and Fig. 2 a horizontal section showing my device in its closed position, and Fig. 3 is a horizontal section showing the same in its open position.

Referring to the drawing, the pipe *d* having the pivots *e* and *f* is journaled in the 55 box *a* having the branch pipes *b* and *c*. The

pivot *f* is extended outside the box and provided with a squared portion *g*. The balls *h* and *i* are surrounded by the holders *k* and *l* pivotally connected to the two lugs *m* and *n* of the pipe. The holders *k* and *l* are 60 guided by the grooves *o* and *p* by means of pins *q* and *r*, respectively. For facilitating their motion small antifriction rollers are carried by the pins.

In the position represented in Figs. 1 and 65 2 when the valve is closed, the balls are located at the ends of the branch pipes, and for obtaining a firm closure a pressure is exercised on them by the lugs *s* and *t* on the pipe. To enable this and to enable the holders to move laterally when the valve is being 70 opened, the holes at the joints of the holders are made oval, as clearly shown in Figs. 2 and 3.

The valve can be packed simply and effectively 75 by packing-rings *u* and *v* consisting for example of asbestos coated with graphite.

I claim:—

1. In a valve, the combination with a 80 valve-box having ports, of a pipe rotatably mounted in the valve-box and adapted to connect together the said ports, and means pivotally mounted on the said pipe and guided by slots in the valve-box for closing 85 the said ports.

2. In a valve, the combination with a valve-box having two oppositely disposed 90 ports and two slots, of a pipe rotatably mounted in the valve-box and adapted to connect the said ports and two holders pivotally mounted on said pipe and guided in said slots, each holder carrying a ball adapted to close one of said ports.

3. In a valve, the combination with a 95 valve-box having two oppositely disposed ports and two slots, of a pipe having two lugs rotatably mounted in the valve-box and adapted to connect the said ports and two holders pivotally mounted on said lugs and 100 guided in said slots, each holder carrying a ball adapted to close one of said ports.

In testimony, that I claim the foregoing as my invention, I have signed my name in presence of two subscribing witnesses.

EMIL BESSERT. [L. S.]
